PROCESS FOR DESULFURIZING AN AROMATIC HYDROCARBON CONTAINING THIOPHENE

Arthur P. Lien, Hammond, Ind., and Bernard L. Evering, Chicago, Ill., assignors to Standard Oil Company, Chicago, Ill., a corporation of Indiana

No Drawing. Application February 12, 1945,
Serial No. 577,580

6 Claims. (Cl. 260—674)

1

This invention relates to a process for the treatment of aromatic hydrocarbons containing heterocyclic sulfur compounds with hydrogen fluoride. More particularly it relates to a process for the chemical conversion and extraction of sulfur compounds. In one embodiment the invention relates to the removal of thiophenes from aromatic hydrocarbons, such as benzene, benzol and the like.

One of the most difficultly removable constituents from aromatic hydrocarbons such as benzene and benzols is thiophene. Thiophene so closely resembles benzene in its chemical and physical properties that for a long time it escaped detection in small quantities in benzenes derived from coal tars. Thiophene may be present in commercial benzenes in proportions up to about 0.5% by weight, usually in the range of about 0.1 to about 0.5 weight percent.

Benzols may contain from a trace to as much as 1.5 or 2 weight percent of thiophene, depending on the source and treatment of the benzols. Benzols derived from low temperature conversions, for example, low temperature coal carbonization, have been found in some cases to contain no appreciable quantity of thiophene. Benzols are derived from light oil fractions obtained by the distillation of coal tar and also from coal and town gases obtained from coking or gasifying coal, e. g., to make carbureted water gas. Benzols contain benzene, toluene, xylenes, and relatively small proportions of unsaturates, paraffins and naphthenes. Normally, the aromatics constitute about 50 to 90 volume percent of benzol. The aromatics are present in variable proportions, but normally the predominating aromatic is benzene, followed in turn by toluene and xylenes. In the careful fractionation of benzols to produce commercial benzene, thiophene distills with the benzene fraction and must be removed to provide chemically pure benzene or nitration grade benzene.

One of the objects of our invention is to provide an improved process for the removal of heterocyclic sulfur compounds from aromatic hydrocarbons. Another object is to provide a new process for the preparation of a synthetic resin from thiophene. A further object is to remove thiophene from association with aromatic hydrocarbons, particularly monocyclic aromatic hydrocarbons, such as benzene, or hydrocarbon mixtures containing benzene, e. g., motor benzol. An additional object is to provide a process for the preparation of benzene in a substantially chemically pure condition. Further objects of our in-

2

vention will become apparent as the description thereof proceeds.

We have discovered a process for desulfurizing aromatic hydrocarbons which are contaminated by thiophene, which process comprises treating said aromatic hydrocarbons with liquid hydrogen fluoride in quantity sufficient at least to form a distinct liquid phase. By the term "desulfurizing," we mean a process of substantially reducing or eliminating sulfur or sulfur compounds. Briefly, we have found that at room temperature (about 70° F.) or higher temperatures, thiophene undergoes a complex chemical conversion upon contact with liquid hydrogen fluoride. This conversion results in the formation of hydrogen sulfide and the production of a resin which is soluble or dispersible in the liquid hydrogen fluoride. At temperatures below room temperature, liquid hydrogen fluoride may effect substantial extraction of thiophene and the like from aromatic hydrocarbons accompanied by a reduced extent of chemical conversion of the thiophene or by substantially no conversion at low temperatures. It is preferred to effect the conversion of the thiophene in the presence of a diluent, such as an aromatic hydrocarbon or mixture of aromatic hydrocarbons, which diluent is sparingly soluble in liquid hydrogen fluoride.

Our process will hereinafter be described with reference to a solution of thiophene in an aromatic hydrocarbon, e. g., as in commercial benzene or benzols. The process hereinafter described may be carried out batchwise or in multistage or continuous operations. In multistage operations, hydrogen fluoride may be added in increments with or without resin separation between stages. In our process we employ substantially anhydrous liquid hydrogen fluoride as a conversion catalyst and extraction solvent; accordingly, we prefer to effect our process under substantially anhydrous conditions. Suitable processing temperatures fall within the range of about -30° F. to 300° F., preferably 60° F. to 120° F. Commercial benzenes are advantageously treated at temperatures between about 45 and 180° F., preferably about 60° F. to about 120° F. We employ pressures in the hydrogen fluoride treating zone sufficient to maintain the hydrocarbon and the hydrogen fluoride in the liquid phase. Operations may be effected at substantially atmospheric pressures when using room temperatures or lower temperatures. However, in commercial operations, it is sometimes desirable to use pressures somewhat above atmospheric, e. g., about 25 to about 50 p. s. i. Of course, at

elevated temperatures, higher pressure will be necessary and may be as high as 1000 p. s. i. at 300° F. At least sufficient hydrogen fluoride is employed to form a distinct liquid extract phase. The amount of hydrogen fluoride based on aromatic hydrocarbon may suitably be between about 5% and about 50% by volume, e. g., about 30% by volume as set forth in the example below. Obviously the volume of hydrogen fluoride employed based on hydrocarbon will be dependent on the amount of thiophene present, larger volumes of hydrogen fluoride being required at high concentrations of thiophene. The necessary time of contact between the hydrogen fluoride and the feed stock will vary to some extent, depending upon the particular aromatic hydrocarbon, the content of thiophene and other sulfur compounds in the feed, the volume of hydrogen fluoride employed per volume of feed stock, and the particular temperature at which treating is effected. However, suitable contact times will usually fall within the range of about 1 to about 120 minutes, preferably about 5 to about 60 minutes.

The thiophene in solution in an aromatic hydrocarbon is vigorously agitated or otherwise contacted with liquid hydrogen fluoride. After contacting, the reaction mixture is allowed to settle in order to form a distinct hydrogen fluoride extract phase. Conventional mixing devices may be employed, e. g., the reaction mixture may be agitated with paddle stirrers, propellers, or turbomixers or the reaction mixture may be pumped at high velocity through tubular conduits containing orifice mixers (baffles) or the like. Alternatively, aromatic hydrocarbons containing thiophene may be passed upwardly through a tower countercurrently to liquid hydrogen fluoride. The tower may be provided with a zone containing suitable packing materials resistant to the action of hydrogen fluoride. A hydrogen fluoride extract phase separates in the lower portion of the tower and the treated aromatic hydrocarbons pass from the upper portion of the tower. The hydrogen fluoride extract phase is a distinct liquid phase containing all or a substantial proportion of the materials produced by the extraction and/or chemical conversion of the thiophene and other compounds which may react. In addition, the hydrogen fluoride extract phase also contains sulfur compounds other than thiophene, e. g., mercaptans, and organic sulfides and disulfides if such compounds were present in the feed stock. A portion of the hydrogen fluoride extract phase may be recycled to the conversion zone.

The aromatic hydrocarbons derived from the hydrogen fluoride conversion are treated to remove small amounts of hydrogen fluoride which remain dissolved or dispersed therein. The removal of hydrogen fluoride from the raffinate may be accomplished by heating and stripping off the hydrogen fluoride, which may be recycled. Stripping aids such as inert gases or low boiling liquids may be used. Any traces of organic fluorides can be removed by passing over bauxite. Alternatively, the removal of hydrogen fluoride and organic fluorides may be accomplished by passing the aromatic hydrocarbons over material which may selectively absorb or react with hydrogen fluoride and decompose organic fluorides, e. g., activated alumina, bauxite, solid CaF_2 , KF , NaF , and the like. Alternatively, or in addition, the aromatic hydrocarbons may be washed with an aqueous or alcoholic solution of an alkaline material, such as ammonia or caustic, and then with water. After the separation of

hydrogen fluoride, the treated aromatic hydrocarbons may be subjected to fractionation, if desired. Where the feed stock to the hydrogen fluoride conversion and extraction process is benzol, the processed benzol may be carefully fractionated to separate a benzene fraction of high purity suitable for nitration or other operations requiring the use of pure benzene.

The liquid hydrogen fluoride extract phase, 10 may be variously treated to recover hydrogen fluoride for re-use in the conversion and extraction process and a solid resinous material derived from thiophene and, in part, from certain reactive aromatics and unsaturates which may be present in the feed stock. Thus hydrogen fluoride 15 may be flash vaporized from the extract phase. In another method of operation, the extract may be subjected to distillation in a tower, hydrogen fluoride passing overhead. A carrier liquid may be introduced into the tower at an intermediate 20 point to maintain the resin in pumpable form. A suitable carrier liquid is hydrocarbon oil which is not reactive with liquid hydrogen fluoride, for example, a hydrocarbon oil which has been treated with hydrogen fluoride under conditions similar to those prevailing in the distillation tower to remove constituents reactive with liquid hydrogen fluoride. It is preferable to use a low viscosity hydrocarbon oil for injection into the distillation tower, for example, a heavy naphtha, kerosene, or a light lubricating oil.

Most of the hydrogen fluoride contained in the extract phase is readily distillable therefrom. However, a minor proportion of the hydrogen 35 fluoride appears to be absorbed quite strongly by resinous materials which may be present and another minor proportion of the hydrogen fluoride may be "bound" in the form of organic fluorides. In order to separate or regenerate the hydrogen 40 fluoride bound in the resinous materials or in organic fluorides, it is desirable to maintain bottoms temperatures in the distillation tower of the order of about 200 to about 500° F. Closely bound hydrogen fluoride need not be removed in 45 the hydrogen fluoride extract distillation tower, but may be removed in a separate tower operating at a desired high temperature. A slurry or dispersion of resin in the carrier liquid is withdrawn from the bottom of the distillation tower, 50 cooled, and filtered to separate the resin and carrier liquid for recycle to the distillation tower.

Many benzols contain unsaturates, i. e., olefinic hydrocarbons, in addition to thiophene and other sulfur compounds. These compounds appear to 55 take part in the reaction resulting in the formation of resins from thiophene. However, commercial benzenes which contain thiophene may contain little or no unsaturates. In order to enhance thiophene removal and to increase the yield 60 of resins, as well as to influence their properties, it may be desirable to add a small proportion, i. e., about 0.1 to about 1% by volume based on the benzene, of an unsaturated hydrocarbon. Suitable unsaturated hydrocarbons include amylenes, 65 styrene, indene, isoprene, cyclopentadiene, dicyclopentadiene, and the like.

The following examples are tabulated to illustrate but not to limit our invention. In these examples the feed stock was a synthetic blend 70 of chemically pure benzene and added thiophene, the blend containing 1.78 weight percent of sulfur as determined by the A. S. T. M. Lamp method. The feed stock (1000 cc.) and liquid hydrogen fluoride were mechanically stirred at about 1700 75 R. P. M. in a carbon steel bomb having a capacity

of 1570 cc. provided with separate conduits for the removal of hydrocarbon and hydrogen fluoride liquid extract phases. Sulfur contents were determined by the Lamp method (A. S. T. M. test D-90-41T described in A. S. T. M. Standards (1942), part III, page 977).

Expt.	cc. HF Added to Reactor	Contact Time, Min.	Temp., ° F.	Wt. Per Cent S
Feed.....				1.78
1.....	150	30	75	0.065
2.....	150	30	75	0.041

In experiment 1, it was found that on opening the bottom valve of the reactor, hydrocarbon rather than hydrogen fluoride came out. In carrying out experiment 2, 150 cc. of additional fresh hydrogen fluoride was added to the contents remaining in the reactor. This time a definite hydrogen fluoride phase separated and it appeared to be quite thick and viscous. After evaporation of the hydrogen fluoride from the extract phase, a solid residue remained. On taking the reactor apart, after washing and heating to eliminate hydrogen fluoride, it was found that a large amount of the solid material lined the reactor walls. The fact that a bottom HF layer did not separate after experiment 1 is thus explained, in that the thiophene present reacted to form a thick, heavy condensation product, or resin, and the HF present was bound or dissolved in this product, the resulting mixture being so thick it adhered to the reactor walls on being thrown outward by action of the stirrer. In experiment 2, the additional HF brought about sufficient fluidity of the HF-resin solution to give a separable bottom layer.

The solid resins produced in the experiments were milled, refluxed with water and dried to obtain a light brown powder. The solid resins derived from thiophene are high melting and not soluble in the common solvents such as acetone, benzene, naphtha, alcohol, or carbon tetrachloride. These resins are thus adapted particularly well to uses requiring a high degree of thermal and solvent stability.

We have observed that the total weight of resinous material recovered on treatment of a thiophene containing aromatic hydrocarbon with liquid hydrogen fluoride is in excess of the weight of thiophene present in the aromatic hydrocarbon. This gain in weight is all the more surprising in view of the fact that part of the original weight of the thiophene is lost as hydrogen sulfide as evidenced by the strong odor of hydrogen sulfide evolved from the reaction products. It is conceivable that part of the thiophene is converted by the catalytic reaction of hydrogen fluoride into diacetylene and hydrogen sulfide and that the diacetylene thus formed may undergo an alkylation reaction with undestroyed thiophene and/or aromatic hydrocarbons. The participation of an aromatic hydrocarbon in the reaction might well explain the gain in weight. It should be understood, however, that we do not intend to be bound by any theory concerning the resinsification reactions.

It will be appreciated that the resins derived from thiophene may be compounded with plasticizers, fillers, pigments, antioxidants and the like, as in the formulation of other plastics. In addition, it may be possible to increase the resin yield and influence the properties of the resin by the inclusion of co-reactive materials such as unsat-

urates with the feed to the hydrogen fluoride conversion and extraction process.

In the course of our process, sulfur compounds other than thiophene, particularly heterocyclic sulfur compounds, are chemically converted and/or extracted from aromatic hydrocarbons. The sulfur compounds present in addition to thiophene may include alkyl thiophenes, such as methyl and dimethyl thiophenes, and various alkyl mercaptans, thioethers and disulfides.

It will be apparent that we have provided a novel process for the conversion of thiophene to a synthetic resin and also a process for the removal of thiophene from its solutions in aromatic hydrocarbons having very similar chemical and physical properties. We have also provided a novel, efficient, and economical process for the conversion of commercial benzene or benzol to pure benzene suitable for further chemical operations such as nitration or conversion to dyes.

We claim:

1. A process for desulfurizing an aromatic hydrocarbon containing thiophene, which process comprises contacting said hydrocarbon with at least about 30 volume percent of anhydrous liquid hydrogen fluoride based on said aromatic hydrocarbon in a contacting zone under sufficient pressure to maintain the liquid phase whereby the thiophene is chemically converted to a resin dispersed in a distinct extract phase predominating in liquid hydrogen fluoride, separating said extract phase, subjecting said extract phase to distillation conditions of temperature and pressure in a distillation zone to vaporize hydrogen fluoride from said extract phase, introducing into said distillation zone a hydrogen fluoride-treated hydrocarbon oil in quantity sufficient to disperse resin which tends to separate in said distillation zone upon evaporation of hydrogen fluoride from said extract phase, liquefying hydrogen fluoride derived from said distillation zone and recycling said liquefied hydrogen fluoride to said contacting zone.

2. A process for desulfurizing benzol which contains thiophene, which process comprises contacting said benzol with at least 30 volume percent of substantially anhydrous liquid hydrogen fluoride, whereby hydrogen sulfide is generated and a resin derived from thiophene and an aromatic hydrocarbon is produced, maintaining sufficient liquid hydrogen fluoride in the reaction zone to disperse said resin and to form a distinct liquid phase, allowing the reaction mixture to stratify, and separating a desulfurized and de-resined benzol layer from a layer of liquid hydrogen fluoride containing said resin.

3. The process of claim 2 wherein said contacting is effected at a temperature between about 45° F. and about 180° F. under a pressure sufficient to maintain the liquid phase.

4. A process for desulfurizing an aromatic hydrocarbon which contains thiophene, which process comprises contacting said aromatic hydrocarbon with at least 30 volume percent of substantially anhydrous liquid hydrogen fluoride, whereby hydrogen sulfide is generated and a resin derived from thiophene and an aromatic hydrocarbon is produced, maintaining sufficient liquid hydrogen fluoride in the reaction zone to disperse said resin and to form a distinct liquid phase, allowing the reaction mixture to stratify, and separating a desulfurized and de-resined aromatic hydrocarbon layer from a layer of liquid hydrogen fluoride containing said resin.

5. A process for desulfurizing an aromatic hy-

drocarbon which contains a heterocyclic sulfur compound selected from the group consisting of thiophene and an alkyl thiophene, which process comprises contacting said aromatic hydrocarbon with at least 30 volume percent of substantially anhydrous liquid hydrogen fluoride, whereby hydrogen sulfide is generated and a resin derived from said heterocyclic sulfur compound and an aromatic hydrocarbon is produced, maintaining sufficient liquid hydrogen fluoride in the reaction zone to disperse said resin and to form a distinct liquid phase, allowing the reaction mixture to stratify, and separating a desulfurized and de-resined aromatic hydrocarbon layer from a layer of liquid hydrogen fluoride containing said resin.

6. A process for desulfurizing an aromatic hydrocarbon which contains an alkyl thiophene, which process comprises contacting said aromatic hydrocarbon with at least 30 volume percent of substantially anhydrous liquid hydrogen fluoride, whereby hydrogen sulfide is generated and a resin derived from said alkyl thiophene and an aromatic hydrocarbon is produced, maintaining sufficient liquid hydrogen fluoride in the reaction zone to disperse said resin and to form a distinct liquid phase, allowing the reaction mixture to

stratify, and separating a desulfurized and resined aromatic hydrocarbon layer from a layer of liquid hydrogen fluoride containing said resin.
